(57) **CLAIM**

The ornamental design for a rear cowl for motorcycle, as shown and described.

DESCRIPTION

FIG. 1 is a perspective view from the top, front, and right-side of a rear cowl for motorcycle;

FIG. 2 is a perspective view from the bottom, front, and left-side thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a front elevation thereof, wherein the rear cowl for motorcycle is shown incorporated into the rear portion of a motorcycle.

The broken lines shown in the drawings illustrate environmental structure and portions of the rear cowl for motorcycle that form no part of the claimed design.

1 Claim, 8 Drawing Sheets
